UNITED STATES PATENT OFFICE.

JOHN DALO, OF PROVIDENCE, RHODE ISLAND, ASSIGNOR TO A AND Z CHAIN COMPANY, OF PROVIDENCE, RHODE ISLAND, A CORPORATION OF RHODE ISLAND.

STRAP-EXTENSION DEVICE.

Application filed February 11, 1928. Serial No. 253,678.

This invention relates to an extension device of the type more particularly employed in a wrist watch strap to extend the length of the strap for passing the strap and watch over the hand of the wearer without disconnecting the ends of the strap from the watch; and has for its object to provide a compact extension member which may have a greater extension than that provided by the unfolding of its parts.

A further object of the invention is the provision of a plurality of foldable sections with one section provided with a plurality of sliding parts such that when the sections are unfolded to extend the effective length of the strap, a still further extension may be afforded by a relative sliding of the parts of one or more of the sections.

A still further object of the invention is the provision of a simple and effective clasp for securing the parts together which will cooperate with the means for securing one of the strap parts to one of the sections.

This invention further consists of the provision of a tip on one of the strap parts which is secured to the end of one of the sections beneath which an extension of another of said sections may be releasably snapped to hold the section in folded position.

With these and other objects in view, the invention consists of certain novel features of construction, as will be more fully described, and particularly pointed out in the appended claims.

In the accompanying drawings:

Fig. 1 is a top plan view of a wrist watch strap with the extension device positioned intermediate its ends.

Fig. 2 is a perspective view of the body section at one end of the device.

Fig. 3 is a perspective view of another end section.

Fig. 4 is a perspective view of one of the parts of the intermediate section.

Fig. 5 is a perspective view of the other part of the intermediate section.

Fig. 6 is a perspective view illustrating the sections assembled and in unfolded position with the sliding parts of the intermediate sections partially extended.

Fig. 7 is a fragmental detail showing the body section and the means by which one end of one strap part is connected thereto also il-

lustrating the hinge connection of the intermediate section thereto.

Fig. 8 is a sectional view on line 8—8 of Fig. 7.

Fig. 9 is a sectional view through the intermediate section showing the relative arrangement of the two parts thereof.

Fig. 10 is a sectional side view showing the relative position of the parts upon their initial movement from folded to unfolded position.

Fig. 11 is a sectional side view similar to Fig. 10 showing the parts in folded position.

It is desirable to provide in a watch strap an extension device which may be manipulated to extend the effective length of the strap to permit it to be passed over the hand of the wearer in removing the watch from the wrist without detaching any of the parts, and in order to provide an increased extension of a plurality of folded sections, I have formed one of these sections with a plurality of sliding parts to permit of further extension after the sections have been unfolded to further extend the effective length of the strap, and I have also provided a clasp for securing the sections in closed position, which consists in extending a portion of one of the sections and snapping it beneath the tip on the end of the strap which is secured to one of the end sections; and the following is a detailed description of the present embodiment of this invention showing one construction by which these advantageous results may be accomplished.

With reference to the drawings, 15 designates an end or body section which is formed with side walls 16 and 17 having openings 18 therein to receive means for securing the end of one part of the strap in adjusted position therein, 19 designates the other end section and between these end sections there is hinged an intermediate section 20 which is composed of two parts 21 and 22 slidably fitted together.

Section 22 has guides formed by folding in the edges 23, as clearly illustrated in Fig. 5, to slidably receive and guide in its movement the section 21. A slot 24 of a length less than the section 21 therein receives a finger abutment 25 cut and bent up from the stock of the section 22, to limit the relative sliding movement of the parts of the intermediate section. Ears 26 are provided on one of the parts of the intermediate section to receive a

pivot pin 27 to hingedly connect it to the side walls of body section 15 while spaced eyes 28 are formed on the other part of the intermediate section to cooperate with an eye 29 on the end section 19 and receive a pintle 30 to hingedly connect section 19 to the intermediate section 20.

The watch strap is formed in two parts 31 and 32, each being provided with suitable means 33 to connect the ends to the strap bars or bails of a wrist watch, the opposite ends of each of these strap parts are connected to the extension device. Strap part 31 is provided with a tip 34 which is suitably secured thereto and provided with a tubular portion 35 with turned-in edges 36 in which trunnions 37 are mounted and forced outwardly by means of a spring 38 which affords a means for adjustably mounting this end of the strap 20 in the body section as the trunnions 37 may be engaged in any one of the holes 18 in the side walls of the body section.

The end of the strap part 32 is provided with a tip 39 secured thereto and provided 25 with a tubular portion 40 through which a pivot pin 41 extends to connect it to the ears 42 on the end section 19.

The sections are held in folded position by a portion 43 of the intermediate section being 30 extended to a sufficient length to snap beneath the tip 40, as is clearly illustrated in Fig. 11, whereby a simple and yet effective lock is provided to hold the sections in folded position.

It will of course be apparent from the foregoing that the sections may be snapped apart, as illustrated in Fig. 10, and then unfolded, as illustrated in Fig. 6, after which the parts 21 and 22 of the intermediate section may be further extended by a relative sliding of the 40 parts one upon the other to increase the effective length of the strap.

In initially snapping the parts from locked position the finger piece 45 extending from the body 15 may be utilized for convenience 45 of operation, if desired.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In an extension device for a wrist watch strap, a plurality of sections hinged together to fold one on another, one of said sections comprising two parts slideable one on the other, means for retaining said sections in folded position and at the same time preventing sliding of the parts one on the other whereby said sections must be unfolded to slide the parts one on the other.

2. In an extension device for a wrist watch strap, a plurality of sections hinged together 65 to be folded one on the other, one of said sec-

tions comprising a plurality of parts slideable one on the other, means permitting free but limited relative sliding movement of the parts of said section only when said sections are unfolded.

3. In an extension device for a wrist watch strap, a plurality of sections hinged together to be folded one on another, one of said sections comprising a plurality of parts slideable one on the other, one of said parts having means for guiding another of said parts in its sliding movement, formations between said parts separate from said guiding means to permit free but limited sliding movement within limits less than the length of one of the parts upon unfolding of said sections, and means for preventing sliding of the parts when folded.

4. In combination, a pair of straps, an extension device comprising a plurality of sections hinged together, the ends of said straps secured to the ends of said device, one of said sections comprising a plurality of parts slideable one on the other, folded-in edges on one of said parts and another of said parts being of a width to extend beneath and be embraced and guided by said folded-in edges in the relative sliding movement.

5. In an extension device for a wrist watch strap, a plurality of sections hinged together to be folded one on another, one of said sections comprising a plurality of parts slideable one on the other, and limiting means for the movement of said parts consisting of a slot in one part extending a portion of the length thereof and a protuberance on the other of said parts extending into said slot, and means for permitting sliding of the parts only when unfolded.

6. In combination, a pair of strap parts, a device comprising a body section having side walls with a plurality of spaced openings therein, a tip carried by an end portion of one of said strap parts, resiliently-mounted trunnions extending from the edges of said tip to engage any one of a pair of the spaced openings in said side walls for adjustment relative to the body section, end and intermediate sections hinged together, means for securing an end of the other of said strap parts to the free end of said end section, means for hinging the intermediate section to said body section, said intermediate section comprising a plurality of relatively slideable parts, and means for limiting the sliding movement of said parts consisting of a slot in one part and a finger on the other part slideable in said slot.

7. In combination, a pair of strap parts, a device comprising a body section having side walls with a plurality of spaced openings therein, a tip carried by an end portion of one of said strap parts, resiliently mounted trunnions extending from the edges of said tip to engage any one of a pair of the spaced openings in said side walls for adjustment

relative to the body section, an intermediate section comprising two parts, one of said parts having a slot therein terminating short of the end thereof, means for hinging said slotted part to said body section, the other of said section parts having an abutment slideable in said slot to limit the movement thereof and its edges folded inwardly to receive and guide said slotted part, and an end section hinged to the section part carrying said abutment, and means to secure the other of said strap parts to the free end of said end section.

8. In combination, a device comprising a plurality of sections hinged together to fold one upon the other, a pair of strap parts, means for securing one end of one of the strap parts to one of the sections, means extending transversely of another section for securing an end of the other strap part thereto, and the end of still another section cooperating with said last named strap securing means to lock the sections in folded position.

9. In combination, a device comprising a pair of end sections, an intermediate section hinged at its ends to said end sections to permit folding one on another, a pair of strap parts, means for securing one end of one strap part to one end section, means for securing an end of the other strap part to the other end section, and means extending from the end of the intermediate section to snap beneath the last said strap securing means by a resilient action of the parts to hold the sections in folded position.

35 10. In combination, a device comprising a pair of end sections, an intermediate section hinged at its ends to said end sections to permit folding one on another, a pair of strap

parts, means for securing one end of one strap part to one end section, a tip on the end of the other strap part, means for securing said tip to the other end section, and a portion extending from said intermediate section to snap beneath said tip and secure the sections in folded position.

40 11. In an extension device for a wrist watch strap, three sections hinged together to fold one on another, the section intermediate the end sections comprising two parts slideable one on the other, securing means carried by the end sections for retaining the sections in folded position and preventing sliding movement of the parts of the intermediate section.

45 12. In combination, a plurality of sections hinged together to fold one upon the other, a pair of straps, means for securing one end of one of the straps to one of the sections, another of the sections having two parts slideable one on the other and held against sliding in one direction when said sections are in folded position by said strap securing means, and means for attaching one end of the other strap to yet another of the sections.

50 13. In combination, a pair of straps, an extension device comprising a plurality of sections hinged together to be folded one on another, means securing the ends of said straps to the free ends of said device, one of said sections comprising a plurality of parts slideable one on the other, whereby said sections can be unfolded and said parts slide to expand said device and straps, and means for permitting sliding of the parts only when unfolded.

55 In testimony whereof I affix my signature.
JOHN DALO.
